CLAIM

The ornamental design for an intelligent lock set, as shown and described.

DESCRIPTION

FIG. 1 is a front view of an intelligent lock set embodying another aspect of the design;

FIG. 2 is a back view of the design of FIG. 1;

FIG. 3 is a left view of the design of FIG. 1;

FIG. 4 is a right view of the design of FIG. 1;

FIG. 5 is a top view of the design of FIG. 1;

FIG. 6 is a bottom view of the design of FIG. 1;

FIG. 7 is a front perspective (3D) view of the design of FIG. 1; and

FIG. 8 is a back perspective (3D) view of the design of FIG. 1.

FIG. 9 is a front view of an intelligent lock set embodying yet another aspect of the design;

FIG. 10 is a back view of the design of FIG. 9;

FIG. 11 is a left view of the design of FIG. 9;

FIG. 12 is a right view of the design of FIG. 9;

FIG. 13 is a top view of the design of FIG. 9;

FIG. 14 is a bottom view of the design of FIG. 9;

FIG. 15 is a front perspective (3D) view of the design of FIG. 9; and,

FIG. 16 is a back perspective (3D) view of the design of FIG. 9.

The broken lines depicting portions of the intelligent lock set form no part of the claimed design.

1 Claim, 16 Drawing Sheets
